(57) CLAIM

The ornamental design for a shelf for recreational vehicles, substantially as shown and described.

DESCRIPTION

FIG. 1 shows an upper left, front perspective view of the design of the present invention; and,

FIG. 2 shows an upper front, left perspective view of the design of FIG. 1 mounted on the exterior of an RV.

Broken lines in the drawings show structural connection and environmental features which form no portion of the claimed design.

1 Claim, 2 Drawing Sheets
